UNITED STATES PATENT OFFICE.

CAROLE A. CLARKE, OF MONTREAL, QUEBEC, CANADA, ASSIGNOR TO WESTERN ELECTRIC COMPANY, INCORPORATED, OF NEW YORK, N. Y., A CORPORATION OF NEW YORK.

TRANSMISSION OF PICTURES.

Application filed August 8, 1925. Serial No. 48,939.

This invention relates to transmission systems and more particularly to the transmission of pictures by electrical means.

In the transmission of pictures, it has been found necessary and desirable at times to transmit the same picture a number of times to various stations and over different transmission channels at various speeds and under different conditions of the transmitting medium. For this purpose, there has arisen a need for some permanent record of the signals transmitted in order that they may be available at any time for immediate retransmission.

Such permanent records will be of considerable value in cases where it is desired to maintain a file of pictures available for immediate use at a central station or in case pictures are to be retransmitted from a central distributing station over a number of lines or channels or at different speeds of transmission. This will enable the operator at the distributing station to transmit over any available transmission channel or to adapt the speed of transmission to that most adequately suited to any particular signaling circuit.

Obviously, considerable saving of time results from the use of such a method as it eliminates the procedure of photographing the subject to be transmitted and the operations incident to its being made suitable for transmission purposes.

One of the principal objects of the present invention is the recording of signals for retransmission.

Another object of the invention is the retransmission of picture characteristic signals to reproduce a picture at a distant station.

In methods of carrier current picture transmission heretofore developed, the reproduced picture is a good reproduction of the original, but if magnified, it will be seen that the variations in tone value at the carrier frequency are not sinusoidal in character. In order to retransmit such a picture it must be treated as was the original. In accordance with this invention the variations just mentioned are made to be of a sine wave character and an electric carrier wave of sine form is generated directly therefrom for retransmission purposes. It is a further object of this invention to produce a record

from which a sinusoidal carrier wave may be directly produced.

According to one embodiment of the invention the characteristics of each elemental area of a picture are transmitted as modulations of a voice frequency carrier wave which can be readily transmitted over ordinary telephone lines. The modulated carrier wave is impressed at the distant station on an electrical recorder which functions to record not only the carrier wave modulated in accordance with the tone values of the picture, but also a carrier wave to be later used for synchronizing purposes. The recording element may be an impressionable surface or any other suitable means capable of recording and storing signals for future use.

By means of an electrically operated reproducer, the current characteristics recorded are retransmitted over transmission channels such as ordinary telephone lines to a remotely situated station where the currents are impressed on receiving apparatus for reproducing the picture from the signals received.

With the foregoing objects in view, the invention will be illustrated and described as employed in connection with a picture transmission system such as that disclosed in Patent No. 1,606,227, issued November 9, 1926, to Messrs. Horton, Ives and Long. For the purposes of this case it has been thought sufficient to show only so much of the apparatus and mechanism disclosed in that application as is necessary to a clear and accurate understanding of the present invention.

Referring now to the drawing:

Fig. 1 illustrates one form of sending equipment of a picture transmission system connected by means of any suitable transmitting medium to a recording mechanism located at a distant station.

Fig. 2 illustrates one form of reproducing mechanism at a distant station for retransmitting stored signals.

Fig. 3 is a side view of the recording mechanism.

Fig. 4 is a corresponding view of the reproducing mechanism.

Fig. 5 is a circuit diagram illustrating a further use of the invention.

Referring now to Fig. 1, station A is

shown connected to station B by means of a transmission channel such as telephone lines 10 although the invention is capable of use in connection with radio or any other electrical signaling system. At station A there is located suitable mechanism for the transmission of carrier current waves modulated in accordance with the tone values of the elemental areas of a picture to be transmitted. At station B, there is shown an electrically operated recorder which responds to the carrier current waves transmitted from station A for recording on a record representations of the transmitted carrier current waves. The record shown is in the form of a wax cylinder and is preferably of the type in which the impressions in the wax are lateral cuttings as distinguished from the hill and valley type of record. At station A a modulator 6 is supplied with carrier waves from a carrier oscillator 7 and with picture current from a photo-electric cell 8. For the purpose of clearness the modulator is shown in conjunction with an amplifier serving to amplify the picture currents before being impressed on the modulator. Modulated carrier waves from the modulator 6 are impressed upon the telephone line 10 through a picture channel filter 9 and a terminal repeater 11.

The photo-electric cell 8 is located within a transparent drum 14 which is driven by a shaft 15 to which it is rigidly secured. The shaft 15 is journaled in a carriage 16 slidably mounted upon a stationary rack 17. Secured to the shaft 15 is a gear wheel 18 which meshes with the teeth of a gear 19 secured to a shaft 20. The shaft 20 is threaded for a portion of its length and engages threads formed in one of the uprights 16 so that upon the rotation of shaft 20, a rotary and a lateral movement is imparted to the drum 14. Motive power is supplied to the shaft 20 from a motor 21 preferably of the phonic wheel type through a friction clutch or starting mechanism 22. The starting mechanism 22 is arranged to control the engagement and disengagement of the parts of the friction clutch, thereby controlling the starting and stopping of the transparent drum 14.

Mounted on the transparent drum 14 is a transparent film of the picture to be transmitted. Light from a source 30 is focused by means of a lens 31 upon the film through which it passes to the photo-electric cell 8. The amount of light affecting the photo-electric cell 8 is determined by the light density of the elemental area of the film which is at that instant in alignment with the light source 30. The amount of light falling upon the photo-electric cell 8 in turn determines the amount of current which is supplied to the amplifier modulator 6 and in consequence, the value of current

impressed on the line conductors 10, or in other words the amplitude of the carrier wave. The master fork 25 not only serves to control the current driving the motor 21 but also serves to control the application of a separate and distinct synchronizing current wave through control channel filter 27 and the terminal repeater 11 on the conductors 10 extending to station B.

The modulated picture carrier wave and the synchronizing carrier wave traverse the line 10, the terminal repeater 33 and the amplifier 34 and are impressed directly on the operating coil 35 of the electrically operated recorder 36.

Referring now for the moment to Fig. 3, there is shown diagrammatically, an electromagnetic phonograph recorder having a permanent magnet 38, although an electromagnet may serve equally well. Secured to the magnet 38 are soft iron pole pieces 39-40 and 41-42, preferably laminated, with beveled ends between which is pivotally supported an armature 43, tapered at each end to reduce its mass. The armature 43 is mounted on an elongated bar 44 preferably of a suitable aluminum alloy and is provided with recesses for receiving knife edges upon which it is mounted. The bar 44 is held on its pivots and the armature 43 balanced preferably by means of a resilient supporting member. A pair of windings 45 and 46 are mounted coaxially with the armature between the pole pieces and are connected to the output circuit of the amplifier 34. The bar 44 is turned at right angles and has secured to its other end a stylus holder 47 in which is mounted a stylus cutter 48.

For further details concerning the construction and operation of the recording mechanism just described, reference should be had to Patent No. 1,663,884, of H. C. Harrison, issued March 27, 1928.

The stylus cutter 48 engages a wax record blank 50 which is supported by a drum 51 to which power is communicated from motor 52.

Referring to Fig. 2 the mechanism for retransmitting the reproduction of the matter recorded on the record 50, the transmission of current characteristics over the telephone circuit 59 in accordance with the cuttings on the record and the reproduction of the picture at a distant station will now be described. As shown in Fig. 2, the reproducing mechanism 55, which may be of a similar construction to that previously described in connection with the recording apparatus, has its electrical element connected to the line conductors 59 through amplifier 60 and a terminal repeater 61. The drum 56 on which the record 50 is mounted is driven by power from motor 57 which operates at the proper speed as determined by the retransmitting operator at station B.

This may be the same speed as the speed of the motor driving the cylinder during the recording operation or some other speed different from the speed at which the picture was originally recorded as will be pointed out later. With these conditions satisfied the carrier current waves representing not only the modulated output carrier current wave but also the synchronizing current wave will be impressed on the line conductors 59 extending to station C.

The impulses upon being received at station C pass through a terminal repeater 67 and are impressed on the picture channel filter 68 and the control channel filter 69. Each of these two filters passes only a particular frequency which performs the desired function. The current passed by the control channel filter is amplified and rectified by means of an amplifier-rectifier 70 and impressed on a secondary fork or speed control element 71. The secondary fork 71 thus operates at a definite speed ratio with reference to the master-fork 25 located at station A and serves to drive the motor 72 so that the recording drum will rotate at the desired speed.

Similarly, the motor 72 is connected with the reproducing mechanism through a starting mechanism 73. The starting mechanism 73 is preferably the same as that described at station A. Since this particular part does not form a part of the present invention, further details thereof are believed unnecessary.

The drum 65 which is driven from the motor 72 through suitable gears has mounted thereon a photosensitive surface or film 66. Connected to the picture channel filter 68 is an amplifier 74 serving to control the release of the starting mechanism 73 and the operation of a suitable light valve 75. The light valve controls the amount of light falling on the sensitive surface 66 from a light source 76 in accordance with the signals received thus reproducing the picture.

The operation of the system will now be described. Assume that a transparency 29 of a picture to be transmitted has been secured to the drum 14. When it is desired to start the transmission, suitable mechanism is operated for releasing the starting mechanism 22. The operation of this mechanism not only releases shaft 20 for rotation but also transmits to station B a carrier current wave which is impressed on the electrical recorder 36 and which is recorded on the record 50. The drum 14 and the transparent film are now rotated and moved axially by means of the motor 21 which is driven from the master fork 25. Carrier current modulated in accordance with the current impressed on the amplifier-modulator 6, as determined by the condition of the photo-electric cell 8, passes through the picture chan-

nel filter 9 and is impressed on the terminal repeater 11. Simultaneously, with the impression of the picture carrier current wave on the terminal repeater 11, a second carrier current wave of a different frequency, as determined by the control channel filter 27, is impressed on the terminal repeater. The two carrier current waves are transmitted over the line conductors 10 to station B where they pass through the terminal repeater 33 and amplifier 34 and are impressed on the control element 35 of the electrical recorder 36. Inasmuch as the drum 51 is now rotating the stylus cutter 48 passes over the record blank 50 causing indentations in the form of lateral cuttings to be made in this blank in accordance with the carrier current waves transmitted from station A. The operation just described continues until the transparency 29 has been completely traversed by a beam of light penetrating to the photo-electric cell 8 and impulses in accordance with the tone of each elemental area of the picture have been transmitted to the station B and permanently recorded on the record blank 50.

Assume for example, that it is desired to transmit a picture in accordance with the one previously recorded on the record blank 50 to a distant station C. The record blank 50 is accordingly secured to the drum 56 which is driven by the motor 57. The motor is now started and the stylus 58 allowed to traverse the cuttings in the record 50. The operation of the stylus 58 causes the conversion of the mechanical movements thereof through the action of the coils 45 and 46 into electrical energy having the same characteristics as that controlling the recording operation. Carrier current waves are accordingly impressed on the line conductors 59 through an amplifier 60 and a terminal repeater 61. The impulses received at station C from line conductors 59 pass through terminal repeater 67 where they divide, the picture carrier current passing through the picture channel filter 68 while the synchronizing carrier current passes through the filter 69. At the beginning of the record 50 as previously described, there is recorded a control frequency current which acts on the amplifier 74 to cause the operation of the starting mechanism 73 for releasing the drum 65 for rotation. The picture carrier currents are amplified by means of the amplifier 74 and impressed on the light valve 75 which controls the exposure of the various elemental areas of the light sensitive surface 66 in accordance with the tone values of the original picture. The synchronizing carrier current waves are amplified by means of the amplifier 70, and control the secondary fork 71 so that the motor 72 rotates and moves the drum 65 at the same speed relative to the speed of picture signal transmission as

that at which the drum 14 located at station A moved. Consequently, the respective elemental areas of the light sensitive surface 66 will be accordingly arranged and exposed to 5 faithfully reproduce the original picture.

The speeds of recording and retransmitting signals do not necessarily bear any relation to each other as it is possible to receive signals at one speed and retransmit 10 at some other speed as desired, providing the reproducing drum is rotating at a correspondingly different speed. For example, a transmitting cylinder at station A may be rotating at a speed of one revolution per 15 second and signals may be transmitted with a 1300 cycle carrier. At the receiving station the recording element may rotate at the same speed or slower or faster as desired. But continuing the example, we may 20 consider that the recording drum rotates at half the speed of the transmitting cylinder, that is, once every two seconds, or once for each two revolutions of the cylinder at station A. This is possible since the special 25 relation of the signals on the record is immaterial, the proper sequence only being necessary. If now in retransmitting the signals the record is rotated at one revolution per second which is twice its recording speed, 30 the signals will be transmitted to the line at twice the original speed of recording and the carrier will appear as 2600 cycles per second instead of 1300 cycles as originally transmitted from station A. If, however, 35 there is no transmission channel available for transmitting 2600 cycle modulated carrier, the speed of the record may be increased or decreased to any desired speed in order to make use of an available channel 40 or to transmit signals at a frequency at which the particular transmission channel is most efficient. The recording element may therefore receive and retransmit at any speeds whatever so that signals can readily 45 be transferred from carrier frequency to voice frequency or vice versa or may even be transmitted at speeds suitable for cable transmission.

While the invention has been described as 50 suitable for recording simultaneously both picture signals and synchronizing signals it may be desired to transmit either type of signal by itself. In this case the danger of interference between the picture signals and synchronizing signals will be eliminated. The picture transmitting drum may then be 55 rotated by some constant frequency motor and the speed of rotation indicated to station B so that on retransmission it will simply be necessary to tell the operator at 60 station C the ratio of the speed of the recorded signals to the transmitted signals in order that he may regulate the rotation of the reproducing cylinder to the proper relative speed.

As illustrated in Fig. 5 a number of separate sets of picture transmission apparatus may be connected to the same line for transmitting more than one picture at a time or for simultaneously recording several pictures 70 on one record for simultaneous retransmission. For this purpose two sets of transmission apparatus 80 and 83, which are preferably the same as that included within the dotted rectangle of Fig. 1, both transmit 75 signals impressed to the same line L through terminal repeaters 81 and 84 and filters 82 and 85. The two series of signals will of course be transmitted as modulations of different frequency carrier waves. As 80 shown the synchronizing signal oscillator and filter have been omitted but it is equally possible to operate the system including the synchronizing channels. According to this system of operation the signals from both sets of transmitting apparatus are simultaneously impressed on the line through filters and transmitted to station B where both series of signals may be recorded on one record for simultaneous retransmission or the signals may be separated into their respective channels by filters and recorded on separate records. Such a system is particularly adapted for use in transmitting 85 colored pictures in the form of three color 90 records.

Although the invention has been described and discussed with reference to a particular system, it should be understood that the invention is not limited to use with the particular apparatus illustrated, but may be used in connection with the recording and retransmitting of any type of electrical signals. 100

The term "light" as used herein includes 105 not only radiations within the visible spectrum but also radiations having wave lengths above and below those of the visible spectrum.

It is to be understood that the terms used herein in reference to picture transmission, both in the specification and claims, do not limit this invention to the production of a picture record at the receiver from a picture record at the transmitter. This invention is equally applicable to systems for example, in which a transitory image of a still or moving picture or object is produced at the receiver, as in certain forms of television systems. 115

What is claimed is:

1. In a picture transmission system, means for producing a record in accordance with modulations of a carrier wave as determined by the elemental tone values of a picture or object and in accordance with a separate carrier wave, a transmission line, and means associated with said line for reproducing from said record electrical variations of the same forms as those of said record. 120

2. In a picture transmission system, means for transmitting a carrier wave modulated in accordance with the tone characteristics of a picture or object, means for recording 5 said carrier wave on a record blank in the form of a single continuous impression, and a reproducer for retransmitting the carrier wave in accordance with the impression on said record blank.
- 10 3. In a picture transmission system, means for converting electrical variations into mechanical vibrations in accordance with the elemental tone values of a picture or object, a receiving surface, means for causing 15 said vibrations to effect an impression on said surface to correspond to said electrical variations, a transmission line, and an electrical reproducer for transmitting to said line a carrier wave of the form determined 20 by the impressions on said surface.
4. In a picture transmission system, means for modulating a carrier current in accordance with elemental tone values of a picture or object, a line, means for impressing said 25 carrier current on said line and for simultaneously impressing on said line a synchronizing carrier current, a receiving station with a receiving surface associated with said line, and means at said station responsive to 30 the transmission of said carrier currents over said line for producing a continuous impression in said surface corresponding to the transmitted carrier currents.
5. In a picture transmission system, a 35 transmission line, means for simultaneously impressing on said line picture currents and synchronizing currents, and means for receiving said currents and recording the same in the form of a single continuous wave of 40 substantially sine form.
6. In a signaling system, a transmitting medium, means for simultaneously impressing a plurality of carrier waves of different frequencies on said medium, a receiving surface, and means for recording said simultaneously transmitted waves as a single continuous variation in said surface.
7. In a picture transmission system, means for making a record in the form of a single 50 continuous wave of combined picture and synchronizing currents, and means for reproducing a picture from said single wave record.
8. In a signaling system, sending apparatus, receiving apparatus, means for simultaneously sending picture currents and synchronizing currents, means for making a record in the form of a single continuous wave of the combined synchronizing and picture currents, and means for reproducing a 55 picture on said receiving apparatus under
- control of said single continuous wave record.
9. In a signaling system, sending apparatus, receiving apparatus, means for transmitting from said sending apparatus at a desired frequency, signaling and synchronizing currents, means for making a record of the combined signaling and synchronizing currents, means controlled by said record 65 for retransmitting said currents at any desired frequency, and means controlled by said retransmitted currents for reproducing the signals at said receiving apparatus.
10. The method of transmitting a picture 70 which consists in sending simultaneously at a desired frequency, picture and synchronizing currents to produce a record in the form of a single continuous wave, and retransmitting under control of said record said synchronizing and picture currents at any other frequency as determined by the transmission line characteristics to reproduce said picture.
11. In a picture transmission system, means for simultaneously sending picture 75 and synchronizing currents, means for making at any desired speed a single mechanical record of the combined currents, means for retransmitting said combined currents under control of said record at any speed determined by the transmission line characteristics, and means for reproducing a picture 80 from said retransmitted currents.
12. In a picture transmission system, means for producing picture currents in accordance with the characteristics of a picture 85 or object, a source of carrier current of a particular frequency, means for modulating the current from said source by means of the picture currents, means for making a record 90 of the modulated carrier current, means controlled by the form of said record for reproducing a modulated carrier current of any desired frequency, and means controlled by said reproduced current for reproducing 95 said picture.
13. In a picture transmission system, means for producing at a particular frequency currents varying in accordance with the characteristics of a picture or object, a 100 receiving surface, means for changing said current variations into mechanical vibrations to produce a record thereof in the substance of said receiving surface, a current generator controlled by said record for reproducing said current variations at any desired frequency to reproduce said picture.
- In witness whereof, I hereunto subscribe my name this third day of August A. D., 1925.

CAROLE A. CLARKE.
